UNITED STATES PATENT OFFICE

GEORGE DALTON MYERS, WALTER A. EDWARDS, AND JOHN W. HOBING, OF CINCINNATI, OHIO, ASSIGNORS TO THE EDWARDS MANUFACTURING COMPANY, OF CINCINNATI, OHIO, A CORPORATION OF OHIO

TRAFFIC MARKER

Application filed January 30, 1929. Serial No. 336,092.

This invention relates to a type of traffic marker which is on the surface of the pavement it is intended to mark for zoning purposes, as for example safety zones, street 5 crossings, etc.

The primary object of the marker herein described is to produce such a marker as will lie close to the surface of the pavement it is to mark, so that there is no occasion for obstruction to traffic or unnecessary roughness or unevenness in the pavement surface to which my improved marker may be applied.

A further object is to produce a traffic marker which may be applied at any time to a street surface of any paving material, without destroying any portion of the street surface.

A further object is to produce such a marker as will adapt itself to application to the surface of the pavement in a manner that renders it secure against displacement and which through continued use and the passage of traffic over it, will tend to cause it to become more firmly seated or secured to the pavement.

These and other objects are attained in the traffic marker we have described in the following specification and illustrated in the accompanying drawing, in which:

Fig. 1 is a perspective view of a traffic marker embodying our invention.

Fig. 2 is a partial sectional view showing our improved marker in position on a pavement to be marked.

Fig. 3 is a perspective view of a modified form of traffic marker embodying our invention.

Fig. 4 is a view in partial section showing the marker disclosed in Fig. 3.

Fig. 5 is a view similar to Fig. 2, but showing the manner in which my improved marker is installed on the pavement surface.

Fig. 6 is a partial sectional view showing a modified form of our improved marker.

Fig. 7 is a view showing, partially in section, the marker disclosed in Fig. 6, with its parts in loosely assembled condition ready for attachment to the pavement.

Fig. 8 is a perspective view showing a detail of the marker shown in Figs. 6 and 7.

In the form shown in Figs. 1, 2 and 5, there is a plate 6 which may be of any desired shape, as for example circular, square, triangular, diamond shaped, arrow shaped, or otherwise. This plate preferably has a cross sectional shape such as would disclose its under edges lying downturned or approximately so in order to rest upon the pavement wholly by reason of its support from the edges. This feature is disclosed in Figs. 2 and 4. The purpose of this is so that security of positioning may be obtained with solidity when fastened.

In the center of the plate, or at other suitable points, should the shape of the plate render it advisable, there has been provided a fastening pin 7 which occupies a hole 13 in the plate. This pin spike or nail is of special shape adapting it to the specific purpose of securing the plate to the pavement. The pin has a head 8 which fits within a recess 9 formed within the plate, so that its top surface is preferably flush with the surface of the plate, as shown. Immediately beneath this head is a shank consisting of a short cylindrical portion 10 which terminates in a somewhat longer tapered portion 11 having a reverse taper. By this is meant that the taper extends from a small diameter immediately beneath the portion 10 to a diameter adjacent to the lower end which may be about as large as the diameter of the portion 10. From this point of large diameter of the taper, to the end of the pin, is a short conical end portion 12 which forms the guiding point of the pin when it is driven into the pavement.

In securing the plate in position the pavement may be prepared previously by making a hole 20 of substantially pin depth in its surface, to receive the pin. In the case of soft or yielding pavement material, such a pin hole may be made by merely driving into the pavement a bar of the diameter adapted to receive the pin. Or, if the pavement material is hard, such as concrete or the like, it may be desirable to drill the hole preparatory to receiving the pin. In certain very soft paving material it may be sufficient to merely place the plate in position and to drive

the pin directly into the paving material without having to make the hole previously. In any event the hole, if necessary, shall preferably be of a diameter slightly less than the 5 large diameter of the tapered portions of the pin so that a snug driving fit is secured throughout the entire distance the pin is driven. Thus a snug driving fit is obtained up to the point where the shoulder of the 10 cylindrical portion contacts the pavement surface. From this point further driving action occasions the shearing off of the material surrounding the hole in the pavement and forces it ahead of the cylindrical portion, thus 15 causing it to pack or tamp into the annular space surrounding the long tapered portion of the pin and in this manner form a key packing which locks the pin against withdrawal from the hole. In Fig. 5 we have shown in 20 dotted lines 23 this area which is subject to shearing action, and in Fig. 2, in reverse section lining 22 surrounding the tapered portion 11, we have shown this sheared material packed or tamped around the pin.

25 In Figs. 3 and 4 we have shown a modified form of the invention. The only difference over the form shown in Figs. 1, 2 and 5, lies in the shape of the pin. The modification consists in so shaping the pin that its head 30 14 is of countersunk shape instead of flat as shown in Figs. 1, 2 and 5, and its tapered shank 15 below the cylindrical portion 16 is square instead of round in cross section. The recess 17 in the plate 18 is of course made of 35 countersunk shape to accommodate the head 14. A feature of this pin shape is that it necessitates a pavement hole 19 which may be less in diameter than that needed for the round shank pin. This is because the 40 corners of the square shank will force their way into the material surrounding the hole quite readily and thus leave more paving material around the entrance to the hole to be sheared off and packed or tamped into the hole by 45 the cylindrical portion 16 of the pin, as shown in reverse cross section 24 in Fig. 4.

50 In Figs. 6, 7 and 8 we have shown a form of our invention which has been designed for specific purposes. This marker is primarily 55 intended for use where relatively heavy traffic conditions exist. The marker is designed with two objects in mind. First, the marker has been made to embody great strength. Second, the marker has been designed for 60 rigidity of fastening under severe usage. Three elements are employed. There is a 65 marker plate 25 which is supported by a reenforcing plate 26, both plates being locked together and to the pavement by a locking pin 70 27. The plate embodies nothing different in 75 conformation than plate 18 of the form shown in Fig. 4. However, the reenforcing plate 26 is made to nest against the under face of plate 25, as shown, but is provided preferably 80 with edge indentations 28 which cause the

formation of points or lugs 29 on the top face of the plate and lugs or points 30 on the under face. The 31 and 32 in the respective plates are of a size barely to permit the entrance of the small lower end of the slightly 70 tapered tamping portion 33 of the pin. The countersunk head 34 of the pin is designed to occupy the plate recess 35. The reversely tapered portion 36 and the point 37 of the pin are the same as in pin 7 shown in Figs. 1 75 and 2.

The functioning of the features we have described is shown in the description of the fastening operation now given. First the parts are assembled loosely as shown in Fig. 80 7, with the point of the pin in the previously prepared hole 38 in the pavement. Then the pin is given a blow to drive its tapered portion 33 into the plate holes, thereby wedgely locking the two plates and the pin as an integral structure. This driving is continued, thereby forcing the two plates together and causing the points 29 to enter the metal under surface of the plate 25 somewhat 85 as shown in Fig. 6, thereby also locking the plates against relative rotation. Continued driving of the pin also causes the annular under shoulder of the tamping portion 33 to shear the material of the pavement away from around the edge of the hole 38 and to pack or tamp such material into the space surrounding the reversely tapered portion 36 as shown in Fig. 6, thereby locking the pin against withdrawal. Incidentally, the driving of the pin also causes the two plates to 90 be pressed into the pavement at their peripheries sufficiently to assure their being prevented from tilting or turning, the points 30 on the under edges of plate 26 entering the pavement surface to prevent rotation of the 95 entire structure. Also, the lower edge of the plate 26 surrounding its center hole 32, is brought into engagement with the pavement surface. In this manner the marker plate is supported at three annular support 100 zones or lines of contact with the pavement, the first being at the extreme edge of plate 25, the second being at the extreme edge of plate 26, and the third being at the line of contact of edge 39 of plate 26. A marked 105 advantage thus attained lies in the reinforcement and number of places of support of the marker plate, this eliminating any tendency toward flattening and consequent loosening of the plate, as well as avoiding any 110 tendency of the plate to be gradually pressed further and further into the pavement under heavy traffic conditions eventually thereby causing the plate to become less and less conspicuous as an indicator.

115 It may be pointed out that the character of the pavement material may be of such a hard and crystalline nature, as for example concrete, that a plastic or semiplastic material 120 may have to be employed as a binder or cemen- 125

titious material such as tar or liquid asphalt to secure the necessary adhesion of the pin within its mounting hole through penetration of this binder into the pores of the paving material, adhesion to the pin surfaces and binding of the sheared particles into a homogeneous packing or tamping surrounding the pin as a key to lock it in place. Asphalt paving is of such a nature as to render such separate binder material unnecessary.

5 Another feature of our invention is that the actual fastening and maintenance of the plate in fastened condition is accomplished very effectively by reason of the continual action of traffic passing over the pin and plate, thereby forcing the pin continually to occupy a tight plate-holding position relatively to the pavement surface even should there ever be tendency for it to lift slightly or to loosen.

10 15 20 25 30 35 40 45 50 55 60

This is because of the continual tamping action which the cylindrical portion of the pin gives the material which is acting to key it within the mounting hole.

Although we have described the locking pin as being separately formed, it is quite obvious that it may as readily be formed as a projection on the plate itself, thus making the marker a structure of but one piece, without departing from the spirit and scope of our invention.

Also, although we have suggested but two forms of our invention, it is quite obvious that it may be otherwise varied, the locking pin, for example, being capable of considerable variation as to the shape of its tapered portion or the number of steps or offsets therein. This may likewise be said of the tapered portion which operates to cause the projection or pin to be locked securely during and after the fastening operation.

Having thus described our invention what we claim is:

In combination with a traffic marker plate having a pin receiving hole therein, a fastening pin occupying the hole and consisting of a shank having at one end an enlarged head engaging the plate surrounding the hole, at the opposite end a pointed pavement penetrating portion, adjacent the penetrating portion a reversely tapered portion, and between the reversely tapered portion and the head a tamping portion of cross sectional area larger than the greatest cross sectional area of either of the first mentioned portions, said tamping portion having a sharp edged shoulder adapted to shear and tamp paving material around the reversely tapered portion when the pin is driven into the pavement through the plate.

In testimony whereof we have hereunto affixed our signatures.

G. DALTON MYERS.
